APPARATUS FOR SEPARATING OATS
FROM HULLS

Louis B. Baumhauer, Carroll, Iowa

Application September 8, 1932, Serial No. 632,259

1 Claim. (Cl. 209—284)

This invention relates to apparatus for separating oats from their hulls and has for its object the provision of a simple and easily operated machine in which the grain will be delivered from a grinding machine into a hopper and discharged from the hopper into a separator which will deliver the oats and the hulls into separate receptacles. The invention also provides means whereby the operating mechanism may be easily set in inoperative position when desired. The invention is illustrated in the accompanying drawings and consists in certain novel features which will be fully disclosed.

In the drawings, Fig. 1 is a longitudinal vertical section through an apparatus embodying the invention.

Fig. 2 is a view, partly in plan and partly in horizontal section, on approximately the line 2—2 of Fig. 1.

Fig. 3 is a detail section through the gearing.

The apparatus embodies a supporting frame 1 which may be of any appropriate construction and upon which is mounted a hopper 2 into which the oats and hulls are delivered from the mill. The hopper 2 is set upon a box-like base portion 3 which is carried directly by the supporting frame and through which extends longitudinally the main shaft 4. As shown most clearly in Fig. 1, the bottom of the base member 3 is inclined slightly toward one end and at its lower end is a nozzle or discharge spout 5 through which the material is delivered into a separating cylinder 6. At one end, the main shaft 4 has a driving pulley 7 secured thereto which pulley is adapted to receive motion through a belt 8 driven by any convenient or preferred prime motor. A gear 9 is also secured on the shaft 4 and said gear meshes with a gear 10 mounted loosely upon an intermediate shaft 11 which extends into a horizontal slot 12 in a cross bar 13 forming a part of the main frame, and a nut 14 on the end of said intermediate shaft turned home against the beam 13 serves to secure the shaft in a set position. Upon reference to Fig. 3, it will be noted that the shaft is constructed with an annular shoulder 15 so that, when the nut 14 is turned home, the shaft will be clamped to the opposite sides of the beam. By loosening the nut and shifting the shaft along the slot 12, the gear 10 may be moved out

of mesh with the driving gear 9 and the machine thereby rendered inoperative to permit repairs or cleaning. The gear 10 has a pinion 16 fixed to one side thereof and said pinion 16 meshes with a gear 17 on the end of a driven shaft 18 which is journaled in suitable bearings upon the

main frame and is arranged below the base member 3, as shown in Fig. 1. The driven shaft 18 is equipped at the end remote from the gear 17 with a knuckle 19 forming one member of a universal joint 20 whereby motion is imparted to the shaft 21 which carries the separating cylinder 6. As shown most clearly in Fig. 1, the universal joint 20 is provided with a socket 22 of non-circular cross section in which is received the upper end of the shaft 21 which is also of a non-circular cross section whereby the rotation of the socket will impart rotation to the shaft. The lower end of the shaft 21 is journaled in a suitable bearing 23 secured upon the main frame and the separating cylinder 6 is a drum of foraminous material 15 whereby, as it is rotated, the oats or particles of like size may pass through the sides of the cylinder while the larger hulls and waste matter will pass through the open lower end thereof, it being noted that the cylinder is disposed in an inclined 10 position so that the material fed thereto will gravitate toward the lower end of the same. The separating cylinder or screen is carried by the shaft 21 through the medium of radial arms or spokes 24 which are formed integral with or rigidly secured to the shaft and extend therefrom to the wall of the cylinder which is rigidly secured upon their outer ends. A casing 25 is mounted upon the main frame and houses the cylinder so that dust and fine particles which may be thrown 20 into the air around the cylinder will be prevented from scattering over a wide area and constituting a source of discomfort to the operators.

In use, the mechanism which has been described is arranged adjacent a grinding mill so that the product of the mill may pass directly into the hopper 2 and thence gravitate into the box-like member 3, passing from said member through the spout 5 into the rotatable separating cylindrical drum. Motion being imparted to the shaft 4 through the pulley 7 and the intermediate gearing being set at the inner end of the slot 12, the shaft 18 will be rotated and its rotation will be transmitted through the universal joint 20 and the socket 22 directly to the shaft 21. The 35 separating cylinder or drum will, of course, rotate with the shaft 21 and the oats and hulls will be thereby agitated so that the hulls will flow to and through the open lower end of the cylinder and the oats will pass through the sides 40 of the cylinder in an obvious manner. It will be understood that receptacles will be placed below the separating reticulated cylinder to receive the hulls and the oats, respectively, or, in many 45 instances, the apparatus may be set upon an upper 50 55

floor in a building and bins provided below the separator to receive the respective materials discharged therefrom. The device is exceedingly simple and compact and may be operated with a very slight expenditure of power. When it has been once set in operation, it will continue to operate automatically without any care from an attendant and, when the intermediate gear is set in the inoperative position, the machine 10 will be held in the inoperative position so that it will not be accidentally started and possibly inflict injury upon persons near it.

It will be noted that the bottom of the hopper is very gently sloped so that the material fed 15 into the hopper will not flow therefrom in a rapid stream but will escape slowly so that it will be acted upon by the drum in a very efficient manner instead of flowing directly to and through the open lower end of the drum. The shaft 4, 20 even without projections thereon, will agitate to some extent the material immediately around the shaft so that clogging of the material will not occur, and if it should be desired to rotate the main shaft 4 to agitate the material without 25 rotating the drum, the intermediate shaft 11 may be slid toward the outer end of the slot 12 so that the double gear 10 and 11 will be carried out of mesh with the gears 9 and 17 and the shaft 18, which imparts rotation to the drum,

will consequently be at rest. It is also to be noted that the drum and the driving gearing are at opposite sides of the ends of the hopper. This arrangement permits a relatively large hopper to be used and permits the drum to be brought close to the hopper so that it will not be necessary to provide a long spout to carry the material from the hopper into the drum, nor will it be necessary to cut away or otherwise form the hopper so as to reduce the capacity thereof.

5

10

Having thus described the invention, I claim:—

An apparatus of the character described comprising a supporting frame, a hopper carried by said frame and having its bottom inclined downwardly and terminating in a discharge spout at 15 one end, a downwardly inclined reticulated separating drum arranged at one side of and below the hopper to receive material discharged through said spout, a driving shaft rotatably mounted and extending through the lower portion of said hopper above said spout, a shaft disposed axially through said drum and carrying the drum, a horizontal shaft disposed below the hopper and having at one end a universal connection with the upper end of the shaft in the 20 drum, and means disposed at the other side of the hopper for transmitting rotary motion from the driving shaft to said horizontal shaft.
